UNITED STATES PATENT OFFICE.

THOMAS DE LA MARE, OF TOOELE, UTAH.

CONDUIT-MOLD.

1,118,558.

Specification of Letters Patent. Patented Nov. 24, 1914.

Application filed September 12, 1913. Serial No. 789,551.

To all whom it may concern:

Be it known that I, THOMAS DE LA MARE, a citizen of the United States, residing at Tooele, in the county of Tooele and State of Utah, have invented a new and useful Conduit-Mold, of which the following is a specification.

The present invention appertains generally to molds for constructing conduits, pipe lines, and the like, it being the object of the present invention to provide a novel and improved apparatus for molding a continuous pipe or conduit within a trench.

Another object of the present invention is to provide a unique mold core, which may be contracted after the concrete has set thereover, so as to be readily withdrawn for a new operation.

With the foregoing and other objects in view, which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiments in the accompanying drawing, wherein:

Figure 1 is an end view of the mold, as in use, the cope being shown in section. Fig. 2 is a longitudinal vertical section of the mold as in use. Fig. 3 is a fragmental perspective of the means for locking the core in expanded condition. Fig. 4 is a sectional detail of a modified form of core.

In carrying out the present invention, reference being had in detail to the drawing, there is provided a core embodying a sheet metal sleeve 1 having its bottom split longitudinally from end to end, as at 2. The sleeve 1 may be of any suitable diameter and length, according to the diameter of the conduit or pipe to be molded thereby, and according to the other circumstances. It is preferable that the sleeve 1 have a contractive tension, in order that when it is free, the same will contract so as to bring the edges together.

Novel means are provided for expanding, and locking the sleeve or core in expanded condition, and to this end, a plurality of series of bearings 3 are secured within the respective end portions of the sleeve or core,

and have pivoted thereto the toggle levers or links 4, hub members 5 being disposed within the respective ends of the sleeve or core, and having the respective series of radial ears 6 to which the adjoining ends of the toggle levers or links 4 are pivoted. Bolts or stems 7 and 8 are threaded or otherwise engaged through the respective hub members 5, with their free ends projecting in the same direction and bifurcated. The bolts or stem 7 project away from that end of the sleeve or core, which will be termed the inner end, while the other end of the sleeve will be termed the outer end. The outer end or bifurcated portion of the bolt or stem 7 is deflected or bent angularly, as at 9, and a hand lever 10 is fulcrumed or pivoted to the angular end 9 of the stem 8. The lever 10 is preferably of T-shape, or has the oppositely extending ears or lugs 11, one of which is pivoted within the angular end or bifurcated portion 9. A draft rod 12 is disposed longitudinally within the sleeve or core 1, and has its inner end pivoted to the bifurcated portion of the bolt or stem 7, the rod 12 extending between certain of the outer or forward toggle levers 4, and having its outer or forward end bent angularly, as at 13. The angular end 13 of the draft rod 12 is pivoted to the other ear or lug 11 of the lever 10.

Ordinarily, when the lever 10 is so swung, as to permit the rod 12 to move inwardly, the core or sleeve will be contracted, the hub members 5 moving away from each other to permit such action. However, when the lever 10 is swung to the position indicated in Fig. 2, it will be evident that the ears or lugs 11 in being swung with the lever, will draw the rod 12 outwardly, and will force the outer or forward hub member 5 inwardly, so as to expand the sleeve, the lever 10 swinging into or slightly beyond dead center to lock the sleeve in expanded position. It is thus evident that the sleeve may be readily expanded and locked in such condition, by the lever 10, and that when the concrete has set or hardened about the sleeve or core, the lever 10 may be released to permit the core to contract, whereby it may be readily extracted or withdrawn.

In connection with the improved core, there is employed a cope embodying a transversely arched plate or hood 14 coextensive in length with the core, and having the internal flange 15 at its outer or forward

- 2
- end. The arched or curved cope plate 14 is provided with handles 16 adjoining its ends for convenience in handling the same, and is also provided with a longitudinal opening 17 in its top or crest, upstanding diverging flanges 18 being provided along the edges of the opening 17 to provide a hopper for convenience in pouring the concrete or plastic material into the cope.
- 10 In constructing a conduit or pipe, with the present apparatus, a suitable trench or ditch 19 is dug in the soil, and the bottom of the conduit is first molded or formed in the bottom of the trench 19, as at 20, it being noted that the bottom of the conduit may be constructed of any desired thickness. The core is then placed on the bottom of the conduit, after the same has set, the core being expanded, and the sides of the conduit then being formed between the sides of the core and the sides of the trench. It is to be understood that the present apparatus is employed for molding a continuous conduit or pipe, whereby the conduit 25 may be constructed in attached sections. As seen in Fig. 2, when the core is placed on the bottom of the section under construction, the inner end of the core is engaged within the end of the section previously completed, and after the sides of the new conduit section have been completed, the cope 14 has its inner or rear end set over the newly completed section of the conduit, as seen in Fig. 2, and has its flange 15 set over the forward or outer end of the core to close the end of the space between the core and the cope. The concrete or other plastic material may then be conveniently poured into the cope 14 through the opening 17, and 30 after the cope has been sufficiently filled, the concrete is tamped through the opening 17 to complete the new section of the conduit. It will be evident that as the several sections are constructed, they will be bonded together, so as to form a continuous conduit, it being possible to construct conduits of various lengths and proportions. After the successive sections have set, the apparatus may be removed and repeatedly employed for forming new sections of the conduit, the operation being continued until the conduit is completed.
- In Fig. 4 there is illustrated a modified form of the core. This modified core embodies the split sleeve 1' and the toggle levers or links 4' within the ends connecting the end portions of the sleeve and the hub members 5'. A longitudinal shaft 12' is threaded through the hub members 5', the two threads being right and left handed, 60 and a suitable hand wheel 10' being secured on the outer or forward end of the shaft. Chains or flexible members 22 connect the respective hub members 5' and the end portions of the sleeve 1', to limit the expansion 65 of the end portions of the sleeve, whereby one end of the sleeve cannot expand further than the other end. It is evident that by rotating the shaft 12', the hub members 5' may be moved toward and away from 70 each other, to either expand the sleeve or to permit the same to contract, the chains 22 limiting the expansion of the sleeve. This form of core is particularly useful in connection with conduits of small diameters, 75 while the core above described, is preferable with larger diameters of conduits, inasmuch as the core may be more quickly expanded and permitted to contract.
- Having thus described the invention what 80 I claim as new is:—
1. A mold core embodying a contractible sleeve, hub members within the end portions thereof, toggle links connecting the hub members and end portions of the sleeve, 85 a locking lever fulcrumed to one hub member, and a draft rod connecting the said lever and the other hub member.
  2. A mold core embodying a contractible sleeve, hub members within the end portions 90 thereof, toggle links connecting the hub members and end portions of the sleeve, a locking lever fulcrumed to the outer portion of one hub member, and a draft rod having one end connected to the other hub member 95 and having an angular portion at its other end pivoted to the locking lever whereby the angular end of the draft rod may be swung and held beyond the fulcrum of the lever.
  3. A mold core embodying a contractible sleeve, hub members within the end portions thereof, toggle links connecting the hub members and end portions of the sleeve, a T-shaped lever having one end of its head fulcrumed to the outer portion of one hub member, and a draft rod having one end connected to the other hub member and having its other end provided with an angular portion pivoted to the other end of the 10 head of the lever.
- In testimony that I claim the foregoing as my own, I have hereto affixed my signature in the presence of two witnesses.
- THOMAS DE LA MARRE.
